ANKLE BRACE AND STABILIZER

August L. Schultz, Mitchell, S. Dak.

Application July 22, 1955, Serial No. 523,700

2 Claims. (Cl. 128—87)

This invention relates to an ankle brace and stabilizer, and more specifically, the invention pertains to means for supporting ligaments, muscles, tendons, and tissues positioned proximate the ankle structure.

One of the primary objects of this invention is to provide an ankle brace and stabilizer device of the type referred to above which will also provide means to lift the lateral or medial side of the ankle depending upon which side of the ankle is sprained or otherwise injured.

Another object of this invention is to provide an ankle brace and stabilizer device including the above referred to lifting feature which will prevent sprains in weakened ankles and aid in the healing of the injured or sprained ankle by reducing the tension upon those tissues.

A still further object of this invention is to provide ankle brace and stabilizing means which may be formed of inexpensive material and which is non-complex in construction and assembly, and durable in use.

Other and further objects and advantages of the present invention will become more manifest from a consideration of the following specification when read in conjunction with the annexed drawing, in which:

Figure 1 is a side elevational view of an ankle brace and stabilizing device constructed in accordance with the present invention.

Figure 2 is a cross-sectional view taken on the line 2—2 of Figure 1, looking in the direction of the arrows.

Figure 3 is a fragmentary detail cross-sectional view taken on the line 3—3 of Figure 1, looking in the direction of the arrows.

Figure 4 is a bottom plan view of the ankle brace and stabilizer illustrated in Figure 1.

Figure 5 is a side elevational view of the ankle brace and stabilizer prior to its connection with the knitted elastic ankle stocking.

Referring now more specifically to the drawing reference numeral 10 designates, in general, a conventional knitted elastic ankle stocking having a leg and ankle encircling portion 12 and a foot surrounding section 14. The stocking 10 has the usual heel receiving cut out 16. The ankle brace and stabilizer to which this invention is directed is indicated, generally, by the reference numeral 18 and is affixed to the stocking 10 by cement or other conventional means, not shown, and is formed of foam rubber, plastic material, leather, felt or any other similar flexible materials.

In view of the fact that substantially 90% of ankle sprains are on the lateral side, the illustrated brace and stabilizer is shown and described for use in connection with such sprains. It should be recognized, however, that the same brace and stabilizer could be employed if the sprain were medial and that in such cases, the brace and stabilizer would be connected with the medial side of the stocking.

The brace and stabilizer 18 is integrally formed from a sheet of flexible material (foam rubber, for example) and is seen to comprise a pair of spaced downwardly di-

2

verging side support members 20, 22 integrally connected adjacent their upper and lower ends by the upper and lower substantially rectangular cross-support members 24 and 26, respectively, reference being made to Figure 1 of the drawing. The junction of the side support member 20 with the adjacent end of the cross-support member 26 is enlarged to form a laterally and anteriorly extending substantially semi-spherical lobe 28, and the side support member 22 at its junction with the cross-support member 26 is also enlarged to form a laterally and posteriorly extending semi-spherical lobe 30.

A substantially rectangular cross-brace element 32 is integrally formed with and extends between the side support members 20, 22 intermediate the ends thereof to define the substantially rectangular transversely extending apertures 34, 36.

From the lower end of the cross-support member 26 depends an integrally connected elongated substantially rectangular central body portion 33 having its longitudinal axis displaced forwardly of the vertical longitudinal axis of the aperture 34, reference again being made to Figure 1 of the drawing.

The lower end of the central body portion 33 is integrally connected with the upper end of the brace terminal section 38 which extends laterally of the longitudinal sides of the central body portion and includes the oppositely disposed laterally extending lobes 40, 42 and the longitudinally extended arcuately shaped tip 44.

As has been stated above, the ankle brace and stabilizer 18 is adhesively secured (such as by cement) on a knitted elastic ankle stocking 10 of conventional construction, and in practice, the brace may be cemented to both the medial and lateral sides of the stocking or either side thereof.

The upper portions of the side supporting members 20, 22 taken together with the cross-support member 24 and the cross-brace element 32 act as flexible splints on the adjacent muscles, tendons and ligaments of the wearer's leg. The aperture 34 permits a portion of the fibula to protrude if the sprain is lateral, and if medial, the aperture will allow the tibia to extend therein. The opening or aperture 34 also serves to permit the upper portion of the side supporting members 20, 22 and the cross-brace 32 to fit more snugly around the proximate muscles, tendons and ligaments of the leg.

The anterior lobe 28 supports the tissues in front of the malleoli, either the medial or lateral side thereof depending upon which of the sides of the ankle is injured.

The aperture 36 allows the malleoli to protrude so that the adjacent parts of the central body portion 33 of the brace and stabilizer fits snugly against the proximate tissues thereby giving support especially just below the malleoli.

The lobe 40 comprises an appendage for the purpose of supporting the tissue above and around the cuboid bone in a lateral sprain. If, however, the injury comprises a medial sprain, the lobe 40 serves to support the upper, medial portion of the arch of the foot.

The longitudinally extending member 44 is designed to curve around and become positioned under the lateral portion of the foot next to the cuboid bone. This serves as a lift to the foot and ankle to protect it from turning laterally. Of course, the opposite would be true if the brace were used on a medial sprain.

The lobe 42 is designed to fit under the lateral one-half of the os calcis thereby acting further as a stabilizer since it will not permit the ankle to roll outwardly. The opposite is true if the support is used on a medial sprain.

The lobe 30 is adapted to support the tissues posterior to the ankle joint.

Having described and illustrated one embodiment of this invention, it will be understood that the same is

offered merely by way of example, and that the invention is to be limited only by the scope of the appended claims.

What is claimed is:

1. An ankle brace and stabilizer comprising, in combination with an ankle stocking having leg and foot encircling sections, an elongated substantially rectangular strip of flexible material adhesively secured to said leg and foot sections on the side thereof, that portion of said strip of material affixed to said leg portion being substantially rectangular in configuration and having a pair of vertically spaced transversely extending apertures formed therein, said apertures receiving therein adjacent protruding portions of the tibia and malleoli, said portion of said strip of material having at the lower end thereof oppositely disposed laterally extending lobes, one of said lobes being adapted to support tissues disposed anterior of the adjacent portion of the malleoli and the other of said lobes being adapted to support tissues posterior of said ankle, said lower end of said portion of said strip having an integrally connected central body portion extending and secured to said foot section for engagement against the upper medial portion of the arch of a foot, said central body portion terminating in a cross member including a pair of anterior and posterior extending lobes, said anterior lobe being adapted for positioning under the lateral portion of said foot adjacent the cuboid bone thereof, and said posterior lobe being adapted for positioning under substantially the lateral one-half of the os calcis.

5 10 15 20 25 30

2. An article of manufacture comprising an ankle brace and stabilizer, said brace and stabilizer comprising an elongated substantially open rectangular main body portion including a pair of elongated spaced substantially rectangular side supporting members having an integrally formed cross-support element connecting a pair of their respective adjacent ends, a second cross-support member integrally connecting the other adjacent ends of said side supporting members, a cross-brace having its respective ends integrally connected with said side supporting members intermediate the ends thereof, said second cross-supporting member at the junction of said other ends of said side supporting members being enlarged to provide a pair of oppositely disposed laterally extending lobes, a substantially rectangular central member having one of its ends integrally formed with said second cross-supporting member, said central member having a pair of oppositely disposed laterally extending lobes at an opposite end thereof, and a substantially arcuately shaped longitudinally extending lobe having one of its ends fixedly secured to said central member.
